UNITED STATES PATENT OFFICE.

WILLIAM A. HEIDE, OF DETROIT, MICHIGAN.

CARBURETOR.

Application filed October 1, 1919. Serial No. 327,778.

To all whom it may concern:

Be it known that I, WILLIAM A. HEIDE, a citizen of the United States, residing at Detroit, in the county of Wayne and State 5 of Michigan, have invented a new and useful Carburetor, of which the following is a specification.

This invention relates to carburetors particularly designed for use on aeroplanes 10 adapted to travel at various angles and in inverted positions and also on motor boats and other structures. One of the objects of the invention is to provide a carburetor which will operate efficiently under these various conditions.

A further object is to mount the fuel bowl of the carburetor in a novel manner to maintain the level of the fluid from the fuel practically undisturbed by the movement of the machine on which the carburetor is mounted.

With the foregoing and other objects in view, which will appear as the description proceeds, the invention consists of certain 25 novel details of construction and combinations of parts which will be hereinafter more fully described and pointed out in the claims, it being understood that various changes may be made in the construction 30 and arrangement of the parts without departing from the spirit or sacrificing any of the advantages of the invention.

In the accompanying drawings the preferred form of the invention has been shown.

35 In said drawings—

Figure 1 is a plan view of the carburetor and parts connected thereto, a portion being shown in section.

Fig. 2 is a section on line 2—2, Fig. 1 40 showing one of the trunnions of the carburetor.

Fig. 3 is a section through a portion of the carburetor showing another one of the trunnions.

45 Fig. 4 is a section on line 4—4, Fig. 2.

Referring to the figures by characters of reference 1 designates a holding structure, preferably in the form of a yoke, as shown, and adapted to be bolted or otherwise fixed-

50 ly connected to the aeroplane or other structure in which the carburetor is to be mounted. This supporting structure is provided at one end with a boss 2 in which is secured a bearing sleeve 3 held in place 55 by screws 4 or the like, there being a passage 5 extending through the sleeve for

the reception of one end of a fuel supply pipe 6. A packing gland 7 is provided at the other end of the sleeve and extends around a tubular trunnion 8 projecting from the center of one end of a frame 9. Another tubular trunnion extends from the other end of the frame 9 and is mounted for rotation within the outer end portion of a stepped bore 10. This trunnion has been indicated at 11 and surrounds and is spaced from a tube 12 which extends beyond both ends of the trunnion 11 into the frame 9 and into the bore 10. A third tube is within and spaced from the tube 12, as shown at 13 and projects beyond both ends of said tube 12, and a fourth tube 14 is within and spaced from the tube 13 and projects beyond both ends thereof. All of these tubes 11, 12, 13 and 14 are concentric and those ends thereof within the frame 9 communicate with separate passages 15, 16, 17 and 18 respectively, formed within one end of the frame 9.

The bore 10 is provided in a block 19 secured to the holding structure or yoke 1 at that end thereof remote from the boss 2 and in this block are air inlet ports 23. These air inlet ports are connected by passages 24, 25 and 26 to the bore 10 at points close to the ends of the respective tubes 11, 13 and 14 so as to open into said tubes at all times and irrespective of the rotation of the tubes within the block 19. In each of the passages 24, 25 and 26 is arranged a needle valve 28 adapted to control the flow of air through the ports 23.

The bowl 49 of the carburetor is arranged within the frame 9 and has oppositely extending trunnions 50 and 51 on the top thereof and journaled in the sides of the frame 9. The trunnion 50 is connected by a pipe 52 to the passage 53 in frame 9 and which opens into the trunnion 8. Trunnion 50 has a passage 54 therein which opens into the top of the bowl 49 and the end of this passage is adapted to be closed by a valve 55 carried by a float 56 within the bowl. This float is pivotally supported by a link 57 connected to a bracket 58 within the bowl and when the level of the gasoline in the bowl reaches a predetermined point, the valve will be closed by the float.

The tubular trunnion 51 is provided there-in with concentric tubes 59, 60 and 61 which are spaced apart and of different lengths, each of said tubes being provided with a packing 62 carried by a collar 63, the collars

on the several tubes being connected together to form chambers therebetween into which the respective tubes open. These chambers have been indicated at 64. Tubes 65 connect 5 these chambers with the respective passages 15, 16, 17 and 18.

Those ends of the tubes 59, 60 and 61 and the trunnion 51 overhanging the bowl 49 are closed and disposed in stepped relation and 10 projecting downwardly from them and into the bowl are parallel flat supply tubes 66 which terminate close to the bottom of the bowl and extend through an opening 67 formed in the float 56.

15 By mounting the bowl in the manner described it is free to swing about the axis of the trunnions 50 and 51 and relative to the frame 9. The frame 9, too, is free to swing about an axis extending through the trunnions 8 and 11. Thus the bowl will be maintained by gravity in a horizontal position irrespective of the angle of the structure 1 to the horizontal and even when the said structure is inverted.

20 The bowl 49 is provided with a weight 68 thereunder and supported by bolts 69 the lower ends of which extend into the side of the weight while their upper ends are fastened in ears 70 extending from the cover of the bowl 49. Thus the bowl is maintained 25 level under all conditions.

What is claimed is:-

1. The combination with a supporting structure, of a frame, concentric tubular members extending from one end of the frame and rotatable therewith, one of said members constituting a trunnion of the frame, a tubular member extending from the frame and revoluble in the support and constituting the other trunnion of the frame, said last mentioned tubular member constituting a fuel supply, a float chamber mounted to swing within the frame about an axis at right angles to the axis of the trunnions, 40 concentric tubular members extending from

the float chamber and through the frame, one of said members constituting a trunnion of the float chamber, passages connecting said concentric tubular members of the float chamber with the corresponding tubular members of the frame, a tubular trunnion extending from the float chamber opposite the other trunnion of said chamber and supported by the frame, a passage connecting said tubular trunnion with the fuel supply trunnion, a float operated valve for controlling the flow of fuel through said passage, and separate tubes supported within the float chamber and communicating with the respective concentric tubular members of the float chamber.

2. The combination with a supporting structure, of a frame mounted for rotation therein, oppositely extending tubular trunnions on the frame journaled in the structure, one of said trunnions constituting a fuel intake and the other trunnion constituting a fuel outlet, a self leveling float chamber supported within the frame and mounted for rotation about an axis at right angles to the axis of the trunnions, oppositely extending tubular trunnions projecting from the float chamber and supported by the frame, a passage connecting one of said float chamber trunnions with the fuel intake 70 trunnion, a float operated valve for controlling the flow of fuel through said passage, concentric tubular members spaced from the other tubular trunnion of the float chamber, depending tubes communicating 75 with the respective tubular members and supported within the float chamber, tubular members spaced from and concentric with the tubular fuel outlet trunnion of the frame, passages connecting the concentric 80 tubular members on one trunnion with the corresponding tubular member on the other trunnion.

WILLIAM A. HEIDE.
